UNITED STATES PATENT OFFICE

168,463

NURSERY TOILET

Paul D. La Hue, Dallas, Tex.

Application July 9, 1952, Serial No. 20,527

Term of patent 14 years

(Cl. D4—5)

To all whom it may concern:

Be it known that I, Paul D. La Hue, a citizen of the United States of America, residing at Dallas, county of Dallas, State of Texas, have invented a new, original, and ornamental Design for a Nursery Toilet, of which the following is a specification, reference being had to the accompanying drawings, forming a part hereof.

Fig. 1 is a perspective view of a nursery toilet, showing my new design,

Fig. 2 is a side elevational view of the toilet,
Fig. 3 is a front elevational view of the toilet,

Fig. 4 is a top plan view of the toilet,

Fig. 5 is a rear elevational view of the toilet,

Fig. 6 is a bottom plan view of the toilet,

Fig. 7 is an exploded perspective view of the toilet, and

Fig. 8 is an underside perspective view of the removable bowl and seat of the toilet.

I claim:

The ornamental design for a nursery toilet, as shown.

PAUL D. LA HUE.
